UNITED STATES PATENT OFFICE.

THEODORE C. SEDGWICK, OF NEW YORK, N. Y., ASSIGNOR, BY DIRECT AND MESNE ASSIGNMENTS, OF TWO-THIRDS TO TRUMAN FOWLER, OF ARLINGTON, NEW JERSEY.

ACOUSTIC DEVICE.

Application filed November 5, 1927. Serial No. 231,337.

My invention relates to acoustic devices and especially to an acoustic cone of the type adapted to be operated by electromagnetic driving means for sound reproduction.

5 An important desideratum in the art of electromagnetic sound reproduction, especially where a faithful reproduction of music or speech is desired, is a sound diffusing or distributing means capable of responding efficiently and equally well to substantially all 10 frequencies of the audible range without loss of the tonal qualities or timbre of the original and without the addition of tonal effects due to resonance of such distributing means. The 15 chief object of the present invention is to provide a sound diffusing means of the cone type having the above desired qualities. The present invention attains this object not by rendering the sound emitting member resonant to several frequencies of the audible 20 range, as has heretofore been proposed, but rather by rendering it responsive to and at the same time non-resonant to any of such frequencies, whereby it will reproduce only the 25 impulses imparted to it by the electromagnetic driving means without prolonging or accentuating the vibrations of any particular frequency or frequencies.

Another object of the invention is the provision of a method of forming the cone with predetermined operating characteristics.

Other objects of the invention will be apparent from a perusal of the following specification and the drawings accompanying the 35 same.

In the drawings:

Figure 1 is a front view of the finished cone;

Fig. 2 is a side view looking from the left of Fig. 1;

Fig. 3 is an enlarged scale, detail cross sectional view taken on the line 3-3 of Fig. 1; and

Fig. 4 is a diagram showing the method of forming the blank or surface development of the cone.

Referring to the drawings in detail, and first to Figs. 1 to 3, the cone surface member or cone 1, of special heart-shaped form to be later described, is mounted on a spider frame 50 2 of similar shape, the cone being secured to the frame by a clamping flange 3 (Fig. 4) clamped to the frame within the recess 4 by an overlying clamping plate 5 with an interposed padding 6 of felt, rubber or other suitable padding material. The clamping flange

3 and plate 5 extend around only that portion of the edge of the cone located above the line A-B (Figs. 1 and 2), leaving the edge below this line free, ample freedom being assured by the space between the free edge and the frame determined by the thickness of the padding 6 below the flange 3 which padding extends downwardly only as far as the clamping plate and flange, that is to the line A-B, the free edge of the cone sloping away from the frame below the line A-B. Spaced clamping screws 7 adjustably secure the plate 5 to the frame, enabling the clamping pressure to be adjusted to procure the best operating condition.

70 A mounting post or pedestal 8 extends from the hub portion 9 of the frame toward the apex of the cone and on this pedestal is mounted an electromagnetic driving unit 10 of any known or other suitable form with its connecting rod or driving stylus 11 connected to the apex of the cone in a line concentric with the cone axis, that is, bisecting the angles formed by diametrically opposite cone elements or radii. A pair of eyelets 12 is provided on 75 either side of the frame to enable it to be hung on a wall by a suitable cord not shown, the spacing lugs 13 projecting from the back of the frame acting to space it away from the wall. Obviously, in lieu of the hanging or 80 wall support, the frame may be supported on a stand or pedestal as by securing the hub portion 9 to the top of the pedestal.

85 The shape of the cone 1, which is an important feature of the invention, is such that the cone elements or cone-surface radii vary in length at a constant or uniform rate with the ratio of the longest radius to the diametrically opposite (shortest) radius equal to other than an even fraction and preferably very slightly less than some ratio of even fraction, for example slightly less than 3 to 1. That is, the natural wave length along the shorter radius should not equal any harmonic of the natural wave along the longer radius. This 90 results in preventing harmonic vibrations from being set up along this diameter. While due to the constant increase of one and decrease of the other of diametrically opposite radii, there will be diametric lines on which 95 they will have a ratio equal to a harmonic such as 1 to 2, there will be no sector of appreciable area in which harmonic vibrations may be set up, as an infinitesimal change of angle changes the length and destroys the ratio. 100 105 110

To form a cone having the above characteristics the cone surface is developed in a plane as indicated in Fig. 4, where the spiral curve shown is a graph of the equation $\theta=R$ plotted in polar coordinates, where θ equals the angle of rotation and R = the radius in units of length numerically equal to θ . Starting with the line A—O as the zero position of a line rotating counterclockwise about the point O and increasing, from zero length, one unit length for each degree of rotation, at a position 30 degrees removed from the line A—O the line will equal $O-p'$ or 30 units of length, at 60 degrees it will equal $O-p''$ or 60 units, and so on following the curve of Fig. 4. To produce a curve of any desired size R may be multiplied by a constant without distortion of the curve, the formula thus becoming $\theta=KR$, where K equals the constant. In Fig. 4 the radii are chosen 15 degrees apart except that marked $82^{\circ} 30'$ which is spaced half way between two adjacent 15 degree radii. It is a section of this curve that is used to define the edges or rim of opposite sides of the cone. To form one of the symmetrical halves of the cone, a section must be chosen which lies between two radii less than 180 degrees apart and these two radii brought into the plane of the axis to form the diametrically opposite, longest and shortest, radii of the cone lying on the mid line C—D (Fig. 1). To have these radii in non-harmonic relation I choose a ratio which may be any decimal figure provided it does not interfere with the proposition that there should be no radii equal to an even fraction. In the present instance, the ratio of 2.91 is used because it is found to substantially fulfill the requirements mentioned. This ratio is obtained by using that segment of the spiral figure (Fig. 4) lying to the right between the radii of 240° and $82^{\circ} 30'$. It will be clear that as each radius is equal numerically to the number of degrees their ratio will be as 240° is to $82\frac{1}{2}^{\circ}$ or $\frac{24}{8.25}$ which reduces decimally to 2.91. Thus the ratio is slightly short of the third harmonic. By duplicating this sector on the left side of the 240° radius with the 240° radii coinciding, the two $82^{\circ} 30'$ radii will be 45° apart thus forming a surface development which may be formed into a cone by bringing together the two edges of the sectors defined by the two $82^{\circ} 30'$ radii to form the cone of Fig. 1. In cutting the actual blank allowance is of course made for the clamping flange 3 outside the curve as indicated in dotted lines at 3 in Fig. 4. The joining of the short radial edges may be effected in any known or other suitable manner, for example by overlapping, allowance being made for the overlap in the forming of the blank or surface development.

As the shape of the cone is of the essence of the invention, it is to be understood that the

cone may be fabricated in any manner resulting in a cone of the shape described, as for example by molding or blocking.

It is also to be understood that while I have herein shown and described a particular embodiment of my invention for the sake of disclosure, the invention is not limited to such specific embodiment but contemplates all such modifications and variants thereof as fairly fall within the scope of the appended claims.

What I claim is:

1. A sound functioning cone comprising a cone surface member having a continuous portion of its edge fixed and the remainder free. 80

2. A sound functioning cone comprising a cone surface member of varying radius, all portions having a radius above a given value being fixed at the edges and all portions having a radius below said given value being free at the edges. 85

3. A sound functioning cone comprising a cone surface member having a radius of constant variation and a corresponding constant variation of the radial distance of the center of gravity of successive infinitesimal sectors. 90

4. A sound functioning cone comprising a cone surface member having a portion of long radius and a portion of short radius, the long radius portion being fixed at the edge and the short radius portion being free at the edge. 95

5. A sound functioning cone comprising a cone surface member the radial elements of which on each side of a median plane have their extremities at a varying distance from the apex, varying one unit in length for each degree of rotation. 100

6. A sound functioning cone comprising a cone surface member having two portions, one a continuous portion of long radius and the other a continuous portion of short radius, the portion of long radius being damped and the portion of short radius being undamped. 105

7. A sound functioning cone comprising a cone surface member of a shape such that there is but one position where the radii 180 degrees apart have a given even ratio. 110

8. A sound functioning cone comprising a cone surface member having each half formed from a portion of a spiral subtended between radii less than 180° apart and having a ratio of approximately 1 to 2.91. 115

9. A sound functioning cone comprising a cone surface member having the longest one 120 of each pair of diametrically opposite radial elements damped.

10. The method of forming an acoustic cone from a piece of sheet material which consists in laying off a spiral curve having a radius uniformly increasing from zero length to one unit length for each degree of rotation, to an extent sufficient to include the portion lying between the $82^{\circ} 30'$ radius and the 240° radius, choosing the sector lying between 125 130

these radii and laying a second sector symmetrical to the first with its center and its 240° radius coinciding with that of the first, and securing the two $82^\circ 30'$ radii together to 5 form a cone.

11. The method of forming an acoustic cone from a piece of sheet material which comprises choosing a sector less than 180° of a spiral lying between two radii having a 10 ratio other than an even fraction, laying off on the sheet material two such similar sectors symmetrically on opposite sides of a center line with their centers and longest radial edges coinciding on the line, cutting out the 15 material along the line of the heart-shaped figure thus formed leaving an extended flange portion around a portion of the edge determining the longer radii, bringing the two shortest radial edges together to form a cone, and bending the flange portion at an angle to the cone surface to terminate the cone surface at the line of the spiral.

12. The method of forming an acoustic cone from a piece of sheet material which comprises choosing a sector less than 180° of a spiral lying between two radii having a 20

ratio other than an even fraction, laying off on the sheet material two such similar sectors symmetrically on opposite sides of a center line with their centers and longest radial edges coinciding on the line, cutting out the 25 material along the line of the heart-shaped figure thus formed leaving an extended flange portion around a portion of the edge determining the longer radii, bringing the two shortest radial edges together to form a cone, and bending the flange portion at an angle to the cone surface to terminate the cone surface at the line of the spiral.

13. A sound functioning cone comprising a cone surface member having each half formed 30 from a portion of a spiral subtended between radii less than 180° apart and having a ratio other than an even fraction.

In testimony whereof I affix my signature.
THEODORE C. SEDGWICK.
